Primary Examiner — David G Muller*Assistant Examiner* — Nathan M Johnston(74) *Attorney, Agent, or Firm* — Dale J. Ream(57) **CLAIM**

The ornamental design for a balcony table, as shown and described.

DESCRIPTION

FIG. 1 is a perspective view of a balcony table showing our new design illustrated mounted to a balcony rail apparatus; FIG. 2 is a perspective view thereof;

FIG. 3 is a left side elevation view thereof, the right side elevation view being a mirror image thereof;

FIG. 4 is a left side perspective view thereof; and,

FIG. 5 is an exploded view thereof.

The broken line showing of parts of the drawings is included for the purpose of illustrating use and environment and forms no part of the claimed design.
